UNITED STATES PATENT OFFICE.

FREDERICK W. EHRLICH, OF NEWARK, NEW JERSEY.

DESIGN FOR AN ARM AND CLAMP FOR AUTOSCOPES.

50,377.

Specification for Design.

Patented Feb. 27, 1917.

Application filed September 27, 1916. Serial No. 122,576. Term of patent 7 years.

To all whom it may concern:

Be it known that I, FREDERICK W. EHRLICH, a citizen of the United States, residing in the city of Newark, Essex county, New Jersey, have invented a new, original, and ornamental Design for an Arm and Clamp for Autoscopes, of which the following is a specification, reference being had to the accompanying drawing, forming part thereof.

Figure 1 is a front elevation of my new design.

Fig. 2 is a side elevation.

Fig. 3 is a bottom plan view.

I claim:

The ornamental design for an arm and clamp for autoscopes as shown.

FREDERICK W. EHRLICH.

Witnesses:

LEONORA SCHWARZ,
DEWITT VAN BEUREN.
